DEVICE FOR APPLYING PASTE TO MATERIALS

Charles H. Coulson, Hanover, Pa.

Application July 24, 1933, Serial No. 682,003

1 Claim. (Cl. 91—51)

This invention relates to a device for applying paste to one face of various kinds of material.

An object of the invention is the provision of a device for applying paste to one face of various types of materials in which a cylinder is employed partly immersed in a pasting solution which when revolved will carry the paste up over the surface so that when pieces of material are fed across the outer portion of the cylinder and pressed against the cylinder by a loosely mounted roller paste will be applied to one surface, means being employed for turning the material over so that when it is removed by a traveling carrier the pasted surface will be out of contact with the traveling carrier.

Another object of the invention is the provision of a simple and inexpensive machine for applying paste to one face of various kinds of materials in which a container carrying pasting material has a stepped portion forming a table for feeding materials to be pasted across the outer exposed surface of a revolving cylinder which is partly immersed in the pasting solution, the cylinder being located in an opening formed in the top of the lower stepped portion and an intermediate vertical wall between the tops of the upper and lower sections so that the exposed portion of the cylinder will be in line with the top or table of the upper stepped section, means being employed for reversing the pasted face of the material so that said face will remain out of contact with a traveling carrier which removes the materials away from the pasting machine.

A further object of the invention is the provision of a device for supplying paste to one face of materials in which a container is employed having an opening to receive a cylinder which is revolved in the pasting solution in the container, means being employed for maintaining a predetermined thickness of the film of the paste which is collected by the outer surface of a revolving cylinder.

This invention will be best understood from a consideration of the following detailed description, in view of the accompanying drawing forming a part of the specification; nevertheless, it is to be understood that the invention is not confined to the disclosure, being susceptible of such changes and modifications which shall define no material departure from the salient features of the invention as expressed in the appended claim.

In the drawing:

Figure 1 is a plan view of a pasting machine constructed in accordance with the principles of my invention, and

Figure 2 is a vertical section of the pasting machine taken along the line 2—2 of Fig. 1.

Referring more particularly to the drawing, 10 designates a base member or work table upon which the pasting machine is secured. A con-

tainer 11 is supported on the table and is adapted to be supplied with a pasting solution and this solution is maintained at a predetermined level as indicated by the dotted line 12, shown in Fig. 2. Any form of paste may be employed, depending upon the materials employed and the use of the materials. In the present instance, however, the pasting machine is employed for supplying latex or other similar form of pasting materials to inner soles, box toes, counters, and various other types of fabrics used principally in shoe factories.

The container is composed of an upper stepped section 13 and a lower stepped section 14. A top 15 of the upper section forms a table to receive 15 and feed the materials across the top of a revolving pasting cylinder 16. The lower section 14 is provided with a top 17 and a hingedly mounted door 18. The door 18 closes an opening through which the pasting material is adapted 20 to be supplied to the container 11. The bottom 19 of the container is provided with a drain plug 20. An intermediate vertical wall 21 is located between the tops 15 and 17.

The top 17 of the lower section 14 is provided 25 with an opening 25 and the intermediate wall 21 is also provided with an opening 26 through which projects a portion of the cylinder 16, and the inner edge 27 of the top or table 15 is beveled adjacent the outer surface of the cylinder 16 30 and where said cylinder projects through the opening 26.

A shaft 28 is mounted in bearings 29 formed on the top 17. The shaft is considerably longer than the cylinder 16 so that the bearings will 35 be located away from the pasting solution in the container. The shaft 28 is driven by means of a belt 30, a pulley 31 and a pulley 33 on the shaft 32. The shaft 32 is driven by means of a pulley 32a and a belt 34 which extends to a pulley driven 40 by an electric motor, not shown.

Brackets 36 are supported from the top 17 of the lower section 14 and are provided with an open bearing 37 to receive the ends of an axle 38 carrying a roller 39. It will be noted that the roller is spaced from the cylinder 16 a sufficient distance to engage the material pasted between the roller and the cylinder and the elongated or open bearings 37 permit the roller to apply pressure to the material so that it will receive the paste from the surface of the cylinder 16 while permitting materials of various thicknesses to pass between the roller and the revolving cylinder.

A pair of vertically disposed guides 40 are mounted upon the table 15 and are held in place by straps 41 having slots 42 which receive bolts 43 threaded into the top 15. By this arrangement the guides 40 may be moved towards or away from each other to accommodate material of dif-

5

60

ferent widths. The outer ends of the guides 40 are flared outwardly, as shown at 44. A scraper 50 is carried in tracks 51 secured to the side walls of the container 11 and has a 5 knife edge 52 adapted to be located adjacent the outer surface of the revolving cylinder 16 in order to remove a predetermined quantity of pasting solution from the surface so that the proper amount of paste will be supplied to the materials. 10 A nut 53 is secured to the scraper 50 and receives a bolt 54 having a manipulating knob 55 located externally of the container 11. A flange 56 on the bolt and a collar 57 upon opposite sides of an end wall of the container 11 permits rotation of 15 the bolt 54 but prevents longitudinal movement of said bolt.

The scraper 50 is provided with extensions 58 which engage the ends of the cylinder 16 and remove any paste from said ends.

20 Each bracket 36 has an extension 60 carrying a rod 61. Pivotally mounted on the rod 61 which is pinned at 61^a to the extension 60 is a plurality of reversing guide members 62 in the form of relatively thin blades which have a curved portion 63 and a relatively straight portion 64. These blades are also provided with a lip 65 which is curved to conform to the curvature of the cylinder 16 and lightly rests upon said cylinder, as shown in Fig. 2.

30 A collar 66 is secured by means of a set screw 67 to the rod 61 and is provided with a leaf spring 68 adapted to engage a pin 69 formed on each member 62, whereby the spring 68 will always maintain the tongue 65 in engagement 35 with the cylinder 16. A collar 70 is secured to each member 62 and is received by the rod 61. Spacing washers 71 are located upon opposite sides of the intermediate member 62. A collar 72 is secured by a set screw on the rod 61 and aids in maintaining an end member 62 in position.

40 A conveyor for removing the pasting material from the pasting machine has an inclined portion 75 supported by an idling roller 76 carried by brackets 77 which are secured to the top 15 of the upper section 13 of the container. Brackets 78 are likewise secured to the top 15 and support a driven shaft 79 to which is secured a pulley 80 and one portion of a belt or traveling carrier 50 81 is in engagement with a roller 82^a carried by the shaft 79 so that as the shaft or roller revolves the traveling carrier will be moved. The inclined portion 75 provides sufficient space to permit the operator to feed the material along the table 15.

55 An arm 82 is loosely mounted on one end of the shaft 79 and is pivotally connected at 83 with a link 84. This link has a pivotal connection at 85 with a second arm 86 which is substantially parallel to the arm 82 and is provided with a bearing 87 to receive a shaft 88. A roller 89 is rigidly connected to the shaft 88. A spring 90 tends at all 60 times to move the arm 86 inwardly towards the arm 82 and maintain the roller 89 in close contact with the belt 81 and the driving roller 82^a. An arm 91 extends from each bracket 78 and supports an arm 82 in a horizontal position.

65 A belt 92 connects the pulley 80 with a pulley 93 so that as the shaft 28 is revolved the roller 82^a will be revolved as will be the shaft 79.

70 Standards 100 are mounted on the table 10 and are provided at their upper ends with a sleeve 101 adapted to receive one end of a bolt 102. A nut

103 is threaded onto the bolt for moving the bolt outwardly for a purpose which will be presently explained. The outer end of the bolt is provided with an open bearing 104 to receive a shaft 105 carrying a roller 106. The roller supports the outer end of the traveling carrier 81 and the bolt 102 and nut 103 are employed for the purpose of maintaining the proper tension on the traveling carrier, since the bearings 104 may be moved outwardly or inwardly as may be desired.

10 The operation of my device is as follows: The pasting solution previously described may be poured into the container 11 after the door 18 has been raised. When the proper level of the liquid is obtained the device is ready for use. Power may 15 be applied so that the belt 34 will drive the pulley 32 and likewise the shaft 28 whereby the cylinder 16 will be revolved in the direction indicated by the arrow in Fig. 2. The revolving cylinder will take up the paste and carry it upwardly so that as 20 the strips of material are fed between the guides 40 and onto the cylinder 16, the roller 39 will exert sufficient pressure on the material as the material is fed between the roller and the cylinder to cause the materials to pick up the proper quantity of paste. It will be noted that the roller 39 is spaced from the cylinder 16 so that the roller does not at any time take up any of the paste. After the materials pass beyond the roller 39 the 25 pasted portion of the material will engage the extremely thin edges of the guiding members 62 so that the materials will be bent towards the operator and be reversed in position so that as they are moved upwardly over the roller 39 and guided by the members 62 they will move onto the inclined portion 75 of the traveling carrier 81. The traveling carrier will remove the pasted materials with the pasted side up and transport the materials to that part of the factory where the materials are utilized for some definite purpose.

30 The scraper 50 will always maintain a predetermined thickness of paste on the cylinder and will also clean the ends of the cylinder so that the paste is not wasted in any manner and the bearings for the roller are maintained clean of 35 paste.

35 The lips 65 on the members 62 will lightly engage the outer surface of the cylinder 16 and the pressure of the lips can be regulated by adjusting the sleeve 66 which carries the springs 68.

40 I claim:

45 A device for applying paste to materials comprising a container for paste provided with upper and lower stepped sections and an intermediate vertical wall between the tops of the upper and lower sections, the top of the lower section and vertical wall having openings, a cylinder located in the openings and extending into the container, the top of the cylinder alining with the top of the upper section, means for rotating the cylinder, an idler roller loosely mounted above the cylinder and retained in spaced relation with said cylinder, and spring pressed means pivotally mounted at one side of the cylinder where said cylinder extends through the openings in the vertical wall and top of the lower section, extending 50 over the roller and having a lip resting on the cylinder for maintaining said means in spaced relation with the roller, said means being adapted to guide pasted material away from the roller.
